NILS A. WAHLBERG, OF DERBY, PENNSYLVANIA, ASSIGNOR TO WESTINGHOUSE ELECTRIC & MANUFACTURING COMPANY, A CORPORATION OF PENNSYLVANIA

ARC CONTROL DEVICE

Application filed August 22, 1928. Serial No. 301,289.

My invention relates to arc-control devices and particularly to means for controlling the formation of flashover arcs associated with high-voltage insulators.

5 One object of my invention is to provide a device of the above-indicated character that shall ensure the occurrence of flashover free of the insulator surface, prevent cascading between the units of a series unit 10 insulator, increase the flashover value of an insulator, confine the occurrence of arcover to a definite position or positions, properly control arcs under windy conditions and protect an insulator against both gradual and 15 steep-front voltage surges.

Another object of my invention is to provide an arc-control device for the above-mentioned purposes that shall be constructed of elements having simple symmetrical or 20 standard forms whereby to facilitate and economize manufacture, assembly and renewal of parts and to render the operation of the device effective in service.

In copending application, Serial No. 25 277,016, electrostatic-field-control device, filed May 11, 1928, by Julius J. Torok and assigned to the Westinghouse Electric and Manufacturing Company, is set forth a device upon which this invention is an improvement and to which reference may be had for a more complete understanding of the features herein set forth.

In general, as set forth in the above-identified copending application, the invention 35 includes electrostatic-field-directing and distributing elements, associated with the terminals of an insulator, that are so constructed and related to each other and to an insulator having spaced metal parts distributed therewith as to have substantially the surge-voltage characteristics of sphere gaps relative to each other and the surge-voltage characteristics of needle gaps relative to the above-mentioned distributed 40 metal parts of the insulator.

The electrostatic stress, between the insulator terminals, is so widely distributed and directed through a zone along, but removed from the insulator and so reduced in 45 intensity between said zone and the insula-

tor as to ensure the occurrence of flashover free of the insulator in response to a surge of any kind.

Further, the above-mentioned zone may be limited to a predetermined position, or a 55 plurality of such zones may be provided, each limited to a predetermined position about the insulator, so that an arc of any kind may be caused to occur in any desired position. 60

In accomplishing the above-described results, a structure of new and peculiar form is required which might, if not carefully considered from all angles of construction and operation, result in a structure of relatively 65 expensive manufacture, difficulty of installation and maintenance in effective operating position and condition, and extreme difficulty, if not impossibility, of renewal of damaged parts. 70

Accordingly, it is my aim to provide a structure that shall retain substantially all of the effective and advantageous operating features of the device of the copending application and, at the same time, be so constructed of 75 parts of simple or standard form as to materially economize its manufacture, facilitate its assembly and installation, permit the ready renewal of damaged parts, without the loss of the entire structure, and to otherwise so modify the device as to render the present invention a distinct advance thereover. 80

Figure 1, of the accompanying drawings, 85 is a side elevational view of a structure embodying my invention;

Fig. 2 is a top plan view of the upper portion of the structure shown in Fig. 1, the insulator and other parts being removed; 90

Fig. 3 is an elevational view of a portion of the device adjacent to the lower end of Fig. 1, taken at right angles thereto;

Fig. 4 is a detail cross-sectional view of a portion of the device, taken along the line 95 IV-IV of Fig. 2;

Fig. 5 is a view, similar to Fig. 4, indicating a modified form of structure;

Fig. 6 is a fragmentary sectional view of a slightly modified portion of the device cor- 100

responding to the lower left-hand portion thereof, as viewed in Fig. 2;

Fig. 7 is a view, similar to Fig. 6, of a still further modified form of the structure there-⁵ of;

Figs. 8 and 9 are views, on a reduced scale, of a modified form of the invention, as illus-¹⁰ trated, respectively, at the lower portion of Fig. 1 and in Fig. 3, and

10 Figs. 10 and 11 are views, similar to Figs. 8 and 9, of a further modified form of the invention.

The device comprises, in general, an insulator 2, a member 3 at the upper end there-¹⁵ of for mounting the same on a tower or other usual ground support, a clamp 4 mounted at the lower end of the insulator 2 for supporting a transmission-line conductor 5, and upper and lower electrostatic-field or arc-²⁰ control devices 7 and 8, respectively, of my invention.

The insulator 2 is of a usual series-unit suspension type but may be of other types, my invention being particularly adapted for 25 insulators embodying dielectric and metallic parts distributed through or along the same, such as insulating parts 10 and metal caps 12 and pins 14, respectively, of the insulator 2.

The clamp 4 may be of any suitable type 30 but, as shown, is of a type, which permits the conductor 5 to slip therethrough under certain conditions and permits the main body of the clamp and the conductor to oscillate about an axis through substantially the center 35 of the conductor.

Each of the arc-control elements 7 and 8 is preferably in the form of a loop of modified oval or elliptical shape, having major and minor axes, viewed in one direction, as 40 in Fig. 2, and of substantially U-shape, viewed in another direction, as in Fig. 1, comprising side portions 17 of relatively small outer-surface area and end portions 18 of relatively great outer-surface area.

45 The lowermost surfaces of the upper portions 18 are, preferably, in the same plane, as are also the uppermost surfaces of the lower portions 18, these planes being parallel to each other.

50 The side portions 17 of each of the elements 7 and 8 are preferably disposed entirely at one and at the same side of the plane of the lower and upper surfaces thereof, respectively above mentioned, the portions 17

55 of the upper element 7 being above the lower surfaces, and the portions 17 of the lower element 8 being below the upper surfaces of the end members 18 thereof. The side portions 17 are also provided with portions 19 which 60 merge or extend gradually between the end members 18 and the intermediate portions 20 of the side portions 17, for a purpose to be hereinafter set forth.

Suitable members 21 are connected to the 65 side members 17, as by welding or other suit-

able means, for mounting the upper element 7 to the cap 12 of the upper insulating unit and the lower element 8 to the clamp 4.

The end members 18 are each preferably constructed of standard tubing, as indicated in Figs. 1, 2, 3, 4, 6 and 7, having substantially uniform cross-sectional area throughout or, as indicated in Fig. 5, a similar member 22 may be constructed of sheet metal having at least the main arc-controlling surface portions thereof of uniform cross-sectional area throughout, a consideration being symmetry of cross-section to facilitate and economize manufacture.

The side members 17, while illustrated as 80 of rectangular cross-section, may be of any other suitable shape and, preferably, of the same shape throughout to facilitate and economize manufacture from standard rod or tubing material, a consideration being 85 that they should be of materially reduced surface area, as compared with the areas of the members or portions 18.

In the above-described structure, mainly 90 of Figs. 1, 2 and 3, the upper and lower end portions 18 present relatively extensive conducting surface areas to each other to relatively widely distribute the field between these surfaces and to provide a breakdown characteristic therebetween like the breakdown 95 characteristic between two spheres of relatively great conducting areas. Such characteristics, irrespective of whether the front of a surge wave be steep or gradual, causes the relatively uniform widely-distributed field between the upper and lower coating members 18 to be disrupted before flash-over will occur in a needle-gap field or a field which is more concentrated at the terminals. On the other hand, the field between any of the members 18 and any of the caps 12 is materially more concentrated at the cap; thereby giving this field more the characteristic 105 of a needle gap.

In arcing horns and rings heretofore employed, there has not been sufficient distinction between the type of gap between the horns or rings themselves and between the latter and the metal parts of suspension insulators, so that, in response to a steep-front surge wave, flashover occurred between the caps of adjacent units in an action known as cascading, which is prevented by the device of my invention.

When an arc occurs between either of the 110 oppositely disposed pairs of members 18 during windy conditions, and if the arc hangs on for a sufficient length of time, it may be blown toward the one or the other end of the members 18, to the portions 19 and thence to the intermediate portions 20 of the side members 17, during which transition, the arc is 115 gradually transferred from the large-area member 18 to the small-area member 17 and 120

so attenuated or drawn out in length as to be extinguished.

With the side members 17 secured to the end members 18 by readily operable securing means, such as screws or bolts 23, when one of the parts is damaged by arcs, it may be easily renewed without scrapping the entire structure.

Also, the ends of the side members 17, instead of being secured to the outer surfaces of the end members 18, as illustrated in Fig. 1, may be secured to the inner surfaces of the members 18, as indicated in Fig. 6.

Fig. 7 shows the end members 18 extended slightly beyond the side members 17 and provided with rounded cap members 24 which serve as closure means for, and as means for preventing concentration of the field adjacent to, the ends of the members 18. Other means could, of course, be provided for closing these ends, such as plugs of any suitable character or flat plates fitted over the openings in the ends.

In Figs. 8 and 9, the structure is substantially the same as that shown in the previous figures with the exception that members 25, corresponding to the end members 18, are angularly disposed relative to the positions thereof shown in Fig. 1. In this form, the centers of the members 25 adjacent to the major axis of the device, as shown in Fig. 2, are in the same plane, and the gradual transition of the arcs, under wind conditions, is effected partially by the slope of the end members 25 and partially by the slope of the ends 19 of the side members 17.

In each of the above-described forms, the end members 18 and 25 are of simple-curve form. In Figs. 10 and 11, the structure is also similar to those above described but members 26, corresponding to the end members 18, instead of being of simple curvature, or curved about a single center point, are of compound curvature, or curved about more than one center. Thus, as viewed in plan, as in Fig. 1, the members 26 have curves in a horizontal plane similar to the members 18 and, as viewed in end elevation, as in Fig. 11, they have curves in a vertical plane.

The latter structure localizes the ultimate arcing zone to an even greater extent than in the structures of the previous figures, permits side members 27, corresponding to the side members 17, to be straight throughout the lengths thereof and effects the above-described transition of the arcs under wind conditions while they are still extended between one of the upper and one of the lower members 26.

While I have shown and described particular forms of my invention, changes may be effected therein without departing from the

spirit and scope thereof, as set forth in the appended claims.

I claim as my invention:—

1. An arc-control device comprising an element of substantially loop-shape embodying spaced perimetral portions of substantially the same cross-sectional area throughout, said portions having electrostatic-field-control surfaces in substantially the same plane at right angles to the axis of the loop, and perimetral portions of smaller cross-sectional areas between said first perimetral portions in offset relation to the plane of said surfaces whereby said first perimetral portions are caused to initially receive the arc. 70

2. An arc-control device comprising an element of substantially loop-shape embodying sheet-metal perimetral portions of the same cross-sectional area throughout, said portions having surfaces in substantially the same plane at right angles to the axis of the loop and perimetral members of smaller cross-sectional area than said sheet-metal portions disposed between the same in offset relation to said surfaces whereby said sheet-metal members are caused to initially receive the arc. 75

3. An arc-control device comprising substantially a loop element constructed of end-to-end-related perimetral sections of different cross sectional areas each of substantially uniform cross-sectional area throughout to cause different degrees of electrostatic-stress distribution adjacent thereto. 90

4. An arc-control device comprising a loop including diametrically-opposite perimetral sections of substantially the same cross-sectional area throughout, said sections having electrostatic field-control surfaces in substantially the same plane at right angles to the axis of the loop, and perimetral sections of smaller cross-sectional areas between, and joined to, said diametrically-opposite sections in offset relation to said plane whereby said diametrically-opposite sections initially receive the arc. 100

5. An arc-control device comprising a loop including tubular perimetral sections of the same diameter throughout, said sections having surfaces in substantially the same plane at right angles to the axis of the loop, and perimetral sections of smaller cross-sectional areas between, and joined to, said tubular sections in offset relation to said plane whereby said tubular sections initially receive the arc. 115

In testimony whereof, I have hereunto subscribed my name this 15th day of August 1928. 120
